UNITED STATES PATENT OFFICE.

MARTIN TUFTY, OF ENTWISTLE, ALBERTA, CANADA, ASSIGNOR OF ONE-FIFTH TO
OLAF THOMASSON, OF ENTWISTLE, ALBERTA, CANADA.

DRILL.

Application filed August 8, 1923. Serial No. 656,401.

This invention relates to improvements in drills, and relates more particularly to the type of drill known as a tail drill, and the principal object of the invention is to provide a portable drill of this character whereby pressure can be readily applied to the bit or other tool, and in the following specification the invention will be clearly described, and what is claimed as new will be set forth in the claim forming part of this specification.

Fig. 1 is a front elevation of the tool in question. Fig. 2 is a side elevation of the lower portion thereof, and Figs. 3 and 4 are, respectively, horizontal cross sections on the lines 3—3, and 4—4, Fig. 1.

In the drawings, like characters of reference refer to the same parts.

The frame A of the drill may be made of wood or other suitable material, and the same is adapted to be attached to any suitable support by any suitable means which may be conveniently in the form of brackets B attached to the upper and lower portions thereof, and at the rear side by any suitable fastening means such as nuts and bolts commonly designated C.

Suitably secured to the off-set portion D of the frame A, and extending longitudinally thereof, is a casing E through which operates a crank F which is provided with any suitable handle G. The lower portion of the crank F is threaded as shown at 2, and threaded on this portion 2 is a pressure device, conveniently in the form of a nut 3 preferably circular in form, and it will be understood that the hand may readily grasp this nut and apply pressure to the bit or other tool 4 mounted in the stock 5 which is carried by the lower end of the threaded portion of the crank F. The nut 3 can also be utilized to raise the crank F and its associated parts.

The work rests or support 6 rests against the outer face of the frame A, and the upper portion of said rest or support overhangs the sides of the frame A as shown at

7 as a convenient means to hold said rest or support in alignment with said frame.

Obviously some means must be provided to permit of the adjustment of the rest or support 6, and a convenient means for this purpose comprises a strap 8 more or less U-shaped in form, and the ends of this strap are pivoted to the rest or support 6, by any suitable means such as the bolt 9.

Suitably carried by the rear side of the frame A are a series of lugs 10 vertically spaced apart, and the rear portion 11 of the strap 8 is adapted to engage with any of the said lugs to form a catch to hold the rest or support 6 in adjusted position. The lugs 10 are shown as integrally carried by a plate 12 which is suitably secured to the frame A.

To facilitate the adjustment of the strap 8, the upper edge a of the rear portion 11 thereof is bent outwardly and thus permits of ready clearance with the lugs 10.

The casing E is preferably countersunk in the outer face of the off-set portion D of the frame A, and straps 13 passing through said off-set portion of the frame A may be conveniently employed to secure said casing in place.

It will be obvious that the crank F may be readily given longitudinal and rotary movement within the casing E to permit the tool to function.

Of course the off-set portion D of the tool is in alignment more or less with the work rest or support 6, and this off-set portion permits the crank F and nut 3 to be properly located in respect of the frame A.

What I claim is:

In a machine of the character described: a frame having a stop and a work-rest; a shaft adapted to carry a tool, and being rotatable and freely movable axially in a bearing on the frame, and having a threaded portion; a nut turnable on said portion between the stop and the work-rest to abutting engagement with the stop and freely oppositely toward the work-rest.

MARTIN TUFTY.
